UNITED STATES PATENT OFFICE.

LOUIS A. STANLEY, OF HILLSBORO, OHIO.

OILER FOR AUTOMOBILES.

Application filed June 9, 1924. Serial No. 718,682.

To all whom it may concern:

Be it known that I, LOUIS A. STANLEY, a citizen of the United States, and a resident of Hillsboro, in the county of Highland and State of Ohio, have invented certain new and useful Improvements in an Oiler for Automobiles; and I do hereby declare that the following is a full, clear, and exact description of the same, reference being had to the accompanying drawings, and to the numerals of reference marked thereon, which form a part of this specification.

This invention relates to oiling systems for internal combustion engines wherein the engine fly-wheel is utilized as an oil pump for creating an oil pressure in excess of the gravity head due to the elevation of the oil.

It is an object of this invention to provide an improved device of the class described wherein the oil supply to the engine is controlled by a characteristic of the engine which varies in proportion to the load thereon.

It is also an object of this invention to provide a vacuum operated control valve for use with splash lubricating systems.

It is a further object of this invention to provide an oil collecting chamber having an air dome to equalize the oil supply to the engine under conditions of varying oil levels in the oil sump.

It is another object of this invention to provide in a device of the class described, an air dome in the oil collecting chamber having an air bleed adapted to prevent the device from becoming air-bound.

Heretofore pressure lubricating systems have been proposed wherein the pressure is varied as a function of the intake manifold suction of an internal combustion engine, but such pressure control is inapplicable to splash lubricating systems. It is therefore an object of this invention to provide volume control of a splash lubricating system.

Other and further important objects of this invention will be apparent from the disclosures in the specification and the accompanying drawings.

The invention (in a preferred form) is illustrated in the drawings and hereinafter more fully described.

On the drawings:

Figure 1 is a side view of an engine to which the device of this invention has been attached.

Figure 2 is a rear view thereof with a por-

tion of the fly-wheel housing broken away to show the relation of parts.

Figure 3 is an enlarged view of the device of this invention taken on the line 3-3 of Figure 2.

Figure 4 is a top plan view thereof.

Figure 5 is an enlarged bottom plan view of the device.

Figure 6 is a sectional view on line 6-6 of Figure 3.

Figure 7 is a section on line 7-7 of Figure 6.

Figure 8 is a section on line 8-8 of Figure 6.

As shown on the drawings:

The device of this invention, in general, comprises an oil collecting device, to be described in detail hereinafter, fitted on the fly-wheel housing 10 of an engine 11 and having an oil pipe 12 leading to the front bearing or front end of the splash pan of the engine. The supply of oil admitted to this pipe 12 is controlled in inverse volume relative to the suction or depression in the intake manifold of the engine by means of a valve controlling a passage 13 leading from a nipple 14 to which the pipe 12 is attached. An enclosing casing 15 has a cylindrical bore 16 intercepting the passage 13 at right angles and a plunger operates in this bore, comprising a cylindrical section 17, having a longitudinal groove 18 adapted to function as a dash pot in conjunction with the closed end 20 of the bore 16, and another cylindrical section 21 spaced from the first section to provide a section 22 of reduced diameter and a section 23 of conical form, disposed across the oil passage 13. The cylindrical section 21 is provided with a plurality of grooves 24 adapted to form oil seals, and is also provided with a section of reduced diameter 25 of a length equal to or greater than the maximum movement of the valve, an atmospheric inlet port 26 being provided to this section 25 to neutralize suction on the oil passage due to the intake manifold depression, and thereby prevent leakage of oil past the valve into the intake manifold. The valve is normally urged inwardly towards full open position by a spring 27 seating against a plug 28 having a pipe connection 29 to the intake manifold 30 of the engine.

An oil collection chamber 31 is provided with an oil scoop 32 extending through the fly-wheel housing 10 in the plane of revolution 110

tion of projecting parts of the fly-wheel, preferably the starter gear 33. This arrangement of placing the scoop opposite the starter gear teeth effects a utilization of the 5 greatest effective oil discharge periphery. The scoop is so shaped as to utilize the centrifugal force in the oil flung off the fly-wheel to elevate the oil into the chamber 31 where it is retained at a level determined by 10 the projecting inner end 34 of the scoop 32. The chamber 31 is closed by a cover 35 having a dome 36 directly above the scoop to deflect the oil and form an air dome. Under some operating conditions such as low 15 oil supply, the chamber would become air bound, preventing flow of oil thereinto, so an air outlet passage 36, opening above the normal oil level, is provided in a bolt 37 which serves both to secure the cover in place, and 20 to secure the entire assembly in place on the fly-wheel housing. Yielding washers 38 are provided in recesses around both the bolt and scoop locations to seal against oil leakage at these points, and small projections 39 25 are provided so located with respect to the bolt as to form a triangle with the bolt near the center thereof to form a stable support for the device on the curved surface of the fly-wheel housing.

30 The operation is as follows:

With the parts connected up as described herein and shown in Figures 1 and 2; when the engine is running, the oil in the sump, the level of which extends above the bottom 35 of the fly-wheel, is picked up by the fly-wheel and carried up and thrown off the fly-wheel by centrifugal force, the scoop gathering a considerable quantity of oil and converting the energy of impact into pressure 40 in the chamber 31, the air outlet from the dome being insufficient to entirely dissipate this pressure even when the control valve is nearly closed as under idling conditions with a high intake manifold suction. The pressure 45 within the chamber 31 is sufficient to feed oil, in a quantity determined by the effective passage past the valve, even when the engine is at such an inclination that the oil pipe would not give a gravity flow of oil 50 to the front of the engine.

As the throttle of the engine is opened the suction in the manifold decreases allowing the spring to move the valve towards more open position; the cone-shaped part of the 55 valve giving a graduated opening which allows more oil to flow from the chamber 31 to the front of the engine. With a fully open throttle the maximum flow of oil is assured because under such conditions the intake suction is very low and the engine is developing its maximum power at that speed. When the throttle is closed the piston 60 is drawn up against the pressure of the spring due to increased manifold suction and the flow of oil is determined by the area 65

around the reduced cylindrical section 22 of the valve, which is intended to supply sufficient oil to protect the engine while preventing an excess supply which would cause oil pumping past the pistons due to the high 70 suction in the cylinders with a closed throttle.

As hereinbefore stated, the air dome provided above the scoop serves to maintain a constant supply of oil to the regulating 75 valve even when the oil level in the sump falls below the level capable of furnishing a sufficient supply for gravity feed to the engine. The particular position of the scoop over the gear teeth and the angular position 80 thereof relative to a vertical plane through the axis of the fly-wheel is particularly advantageous in that a certain portion of the oil is deflected to flow over the transmission bands, keeping the same cool and in good 85 condition and thus greatly improving the operation of the automobile.

I am aware that numerous details of construction may be varied through a wide range without departing from the principles of this invention, and I therefore do not purpose limiting the patent granted hereon otherwise than necessitated by the prior art.

I claim as my invention:

1. In combination with an internal combustion engine having a fly-wheel running in an oil sump, a scoop positioned to receive oil thrown off said fly-wheel by centrifugal force, a collecting chamber for the oil from said scoop having an air dome and an air bleeder passage therefrom, an oil delivery pipe, and a control valve therefor adapted to meter the oil in inverse proportion to the engine intake manifold depression.

2. In a splash lubricating system an oil collecting scoop, a chamber receiving oil therefrom, an air dome above the oil level in said receiving chamber, an air bleed from said air dome, and means for metering the delivery of oil from said chamber in response to varying requirements of an engine.

3. In a lubricating system of the class described, an oil collecting chamber, an outlet therefrom and a valve controlling said outlet, comprising a cylindrical dash pot section, a cylindrical piston section, and a tapered section therebetween adapted to be shifted across the outlet to vary the effective area thereof.

4. In a lubricating system of the class described, an oil collecting chamber, an outlet therefrom and a valve controlling said outlet, comprising a cylindrical dash pot section, a cylindrical piston section, a tapered section therebetween adapted to be shifted across the outlet to vary the effective area thereof, and a connection to a source of varying sub-atmospheric pressure adapted to

move said valve in proportion to the pressure drop.

5. In a lubricating system of the type described, a casing having an oil supply passage, a plunger intersecting said passage, a conical section on said plunger adapted to vary the effective area of said passage, and connection to a source of sub-atmospheric pressure for moving said plunger.

10 6. The combination with an automobile including the motor and transmission thereof, of a casing containing oil below the motor and transmission mechanism, a fly-wheel having gear teeth adapted to pick up oil from said casing and an oil control mechanism having an oil scoop so positioned above the gear teeth of said fly-wheel as to deflect a portion of the oil over the transmission mechanism.

20 7. In a lubricating system of the class described, a control valve responsive to the vacuum produced in an engine intake manifold, and means preventing the suction from drawing oil past the valve, comprising an 25 air port in the valve casing between the valve proper and the suction connection.

8. In a splash lubricating system a scoop extending into the flywheel housing, an oil collecting chamber having an air space above the normal oil level therein and a connection 30 forming an air bleed from said air space into the flywheel housing.

9. In a splash lubricating system a scoop extending into the fly-wheel housing, an oil collecting chamber, a cover therefor forming an air dome, and a passaged bolt securing said cover and chamber to the flywheel housing and forming an air relief from said air dome to the interior of said housing.

10. In a lubricating system a housing containing a rotatable member, a casing on the housing adapted to receive lubricant thrown by said rotatable member, an air space in the casing above the normal lubricant level therein, and an air bleed from said air space.

In testimony whereof I have hereunto subscribed my name in the presence of two subscribing witnesses.

LOUIS A. STANLEY.
